UNITED STATES PATENT OFFICE.

CEPHAS V. FITE, OF CHARLOTTE, NORTH CAROLINA.

THERMOSTATIC CIRCUIT-CLOSER.

1,074,544.

Specification of Letters Patent. Patented Sept. 30, 1913.

Application filed January 10, 1913. Serial No. 741,252.

To all whom it may concern:

Be it known that I, CEPHAS V. FITE, a citizen of the United States, residing at Charlotte, in the county of Mecklenburg and State of North Carolina, have invented new and useful Improvements in Thermostatic Circuit-Closers, of which the following is a specification.

This invention relates to improvements in thermostatic circuit closers and has particular application to a device of the class described whereby electric circuits may be closed to sound a bell, gong or other signal in case of fire.

In carrying out the present invention, it is my purpose to provide a thermostatic circuit closer whereby in the event of a super-normal rise in temperature, an electric circuit will be bridged or closed so that an alarm in the circuit may be sounded, and, furthermore, my improved circuit closer embraces the desired features of simplicity, efficiency and durability and may be manufactured and installed at a relatively low cost.

With the above and other objects in view, the invention consists in the construction, combination and arrangement of parts set forth in and falling within the scope of the appended claims.

In the accompanying drawing:—Figure 1 is a perspective view of a circuit closer constructed in accordance with my present invention. Fig. 2 is a transverse sectional view through the thermostatic element. Fig. 3 is a perspective view of the circuit bridging member.

Referring now to the accompanying drawing in detail, the numeral 1 designates a suitable casing or frame composed of side and end members appropriately connected, one to the other, and forming a substantially rectangular structure.

Suitably fastened between the side members of the frame 1 adjacent to one end thereof is a base or block 2 equipped with a binding post 3 and a second binding post 4 suitably spaced apart from the first binding post. Also secured to the block 2 and in electrical communication with the binding post 4 is a metallic plate 5 having one edge upturned as at 6 and then bent upon itself as at 7 to provide parallel members. Disposed between the parallel members formed by the bent portions 6—7 of the plate 5 and connecting such portions as by a screw 8 is

one extremity of a thermostatic element 9 composed in the present instance of a strip of spring steel 10 and a strip of aluminum 11 or other metal capable of expansion under the action of heat. This strip 11 contacts with the steel strip 10 longitudinally of the length of the latter that has the opposite longitudinal edges thereof inturned or bent upon themselves and cut out to form substantially V-shaped gripping fingers 12 designed to contact with the adjacent edges of the steel spring strip 10. A circuit closing or bridging strip 13 is pivoted adjacent to one end upon the plate 5 by a pivot post 14 that has one end cut out to form a contact finger 15 adapted to engage a contact plate 16 secured to the block 2 beneath the binding post 3 and adapted to form one terminal of an electric circuit, the latter including a suitable source of electrical energy and an appropriate form of signal and having the opposite terminal thereof tapped on to the binding post 4. The free end of the bridging strip 13 is upturned as at 17 and cut out to form two lugs 18—18 spaced apart to receive the approximate extremities of the thermostatic element 10.

From the foregoing description, taken in connection with the accompanying drawing, the construction, mode of operation and manner of employing my invention will be readily apparent.

Assuming the device to be connected up to an electric circuit and the surrounding temperature to rise above the normal, it will be seen that the aluminum strip 11 will expand under the action of the heat and so force the spring strip 10 laterally thereby swinging the bridging strip 13 about the pivot post 14 and closing the circuit at the contacts 15 and 16, the terminal or binding post 4 being electrically connected with the binding post 3 by way of the plate 5, the adjacent portion of the strip 13, the contact finger 15 and the contact 16.

It will be noted that the gripping fingers 12—12 being of V-shape and spaced apart permit the aluminum strip to expand with a minimum of frictional resistance between the two metals, while the bridging strip is acted upon in a positive manner by the thermostatic element to close the circuit.

The front and rear of the structure 1 are preferably open and covered by a body of foraminous material such, for instance as a

screen 19, whereby the air may circulate freely about the elements constituting the circuit closer.

While I have herein shown and described a particular form of my invention, it will be noted that I do not confine myself to the precise details of construction herein described and delineated, but modifications and variation may be made within the scope of the claim and without departing from the spirit of the invention.

I claim:—

A thermostatic circuit closer comprising a base block, a pair of binding posts on said block and spaced apart, a stationary contact electrically connected to one of said binding posts, a metallic plate electrically connected to the other binding post and having one edge thereof unturned and then bent upon itself to provide parallel members, a ther-

mostatic element having one end disposed between and secured to said parallel members and the opposite end projected beyond the same, a strip pivotally mounted upon said plate and formed at one end to provide 25 a contact adapted to be moved into and out of engagement with the first-mentioned contact, said strip having the other end thereof disposed adjacent to the outer end of said thermostatic element and upturned and cut 30 out to form lugs spaced apart and designed to receive the free extremities of said thermostatic element.

In testimony whereof I affix my signature in presence of two witnesses.

CEPHAS V. FITE.
